(57) **CLAIM**

The ornamental design for a fluid delivery nozzle, as shown and described.

DESCRIPTION

FIG. 1 is a top, front and left side perspective view of a fluid delivery nozzle showing my new design with the top side rotated slightly toward the viewer;

FIG. 2 is a front view thereof;

FIG. 3 is a top view thereof;

FIG. 4 is a bottom view thereof;

FIG. 5 is a rear view thereof, shown rotated 180 degrees in a top-down position;

FIG. 6 is a left side view thereof; and,

FIG. 7 is a right side view thereof.

The broken lines in the drawings depict portions of the fluid delivery nozzle that form no part of the claimed invention.
